Atty.

UNITED STATES PATENT OFFICE.

WILLIAM S. TOWNSEND, OF WASHINGTON, DISTRICT OF COLUMBIA.

NOZZLE FOR FILLING-HOSE.

1,319,439.

Specification of Letters Patent. Patented Oct. 21, 1919.

Application filed April 16, 1919. Serial No. 290,407.

To all whom it may concern:

Be it known that I, WILLIAM S. TOWNSEND, a citizen of the United States, residing at Washington, in the District of Columbia, have invented certain new and useful Improvements in Nozzles for Filling-Hose, of which the following is a specification.

My invention relates to the nozzles of 10 gasolene hose.

The objects of the invention are to provide a nozzle for gasolene hose which will be self-supporting when inserted in the opening of a motor vehicle tank; to provide 15 such a nozzle with an automatically closing valve having an actuating device to engage the top of the tank when the nozzle is in place and open the valve to permit the flow of gasolene therethrough; also to provide 20 the nozzle with a transparent portion between the inlet end and the valve and finally to provide the outlet or mouth of the nozzle with an internal drip receiving flange or cup.

25 These objects I accomplish by means of the construction shown in the accompanying drawing, in which:

Figure 1 is a longitudinal vertical section through the nozzle in position on a tank.

30 Fig. 2 is a detail view of the valve removed.

1 designates the nozzle of suitable size and material and having a downward curve at its discharge end. About midway of the 35 length the nozzle is provided with an enlarged portion 2 provided with a diagonally arranged valve seat 3 and a crossbar 4. The valve 5 seats on the seat 3 and has a forwardly extending stem 6 guided in an aperture 7 in the crossbar 4 and also guided in a bearing 8 in the lower side of the nozzle. The outer extremity of the valve stem 6 terminates in a transverse foot 9 adapted to rest upon the upper side of the tank to be 40 filled and support that side of the nozzle as well as to open the valve or raise it from its seat. The valve is returned to the seat by the spring 10 mounted on stem 6 between the lower side of crossbar 4 and a collar 11.

45 The nozzle 1 is provided on its upper side or side opposite the foot 9 with a fulcrum point 12 adapted to engage the under side of the tank top when the nozzle is inserted through the opening therein, as clearly 50 shown in Fig. 1. When the nozzle is in this

position its weight and that of the hose will exert a downward pressure and this will cause the valve stem to move upwardly and unseat the valve against the pressure of its spring. Having thus set the nozzle, the operator may leave it and attend to the gasolene pump now so commonly employed for the dispensing of this commodity.

In order that the flow of the gasolene through the nozzle may be seen, I provide 65 the inlet end thereof with a glass section 15 of flattened spherical form, and beyond this is the coupling 16 for connection with a hose 17.

The mouth or outlet of the nozzle is provided with an internal drip cup 18, which may be formed by an upturned annular flange made lower or notched at one side, as at 19, for the discharge of the contents of the cup. This cup 18 is merely to catch 75 the final drops of gasolene remaining in the nozzle at the end of the filling operation and after the nozzle has been removed from the tank so that these drops will not spill on top of the tank, which is so often located beneath the vehicle seat. Any liquid remaining in the cup after a discharge may be emptied therefrom by inclining the nozzle to the right to bring the recess 19 below the level of the liquid so remaining in the cup. 80 The cup is filled, of course, during and at the end of every discharge.

So far as I am aware, there is no gasolene hose nozzle provided with an automatic valve and means for sustaining the nozzle 90 in position and holding the valve open, though can nozzles have had valves capable of being opened by holding the can in pouring position with the valve actuator against the vessel being filled and pushing on the 95 can to operate said actuator. Vessels have also been raised against a valve-actuator mounted on a faucet to open the valve and fill the vessel and all such are disclaimed.

Of course, the nozzle could be attached to 100 filling hose generally.

What I claim is:

1. A nozzle for filling-hose provided at its lower outer portion with means to engage the under side of the top of a tank to be 105 filled at its filling opening, and having a self-closing valve provided with an external actuating means located at a point opposite the said tank-engaging means and adapted to rest on top of the tank adjacent to the 110

filling opening, to open the valve automatically when the nozzle is placed in position.

2. A nozzle for filling-hose provided at its lower outer portion with a laterally extending fulcrum to engage the under side of a tank top at the filling opening, and a downwardly closing valve within the nozzle and provided with an actuating stem extending through the opposite side of the nozzle from said fulcrum to lift the valve when the nozzle is held in position on the tank.

3. A nozzle for filling-hose provided at its lower outer portion with a laterally projecting fulcrum to engage the under side of a tank top at the filling opening, a diagonal valve seat within the nozzle, a valve to close down on the seat and having its stem ex-

tending diagonally out through the lower side of the nozzle and having a foot opposite the said fulcrum to rest on top of the tank at the opposite side of its filling opening.

4. A nozzle for filling-hose provided with a self-closing valve provided with an actuating device to engage the top of a tank adjacent to the filling opening and automatically open the valve by the weight of the nozzle, and means on the nozzle at a point below and beyond said valve-actuating device to engage the inner side of the tank at its filling opening and cause the nozzle to be held in place against the pull or strain exerted by a filling-hose on said nozzle.

In testimony whereof I affix my signature.

WILLIAM S. TOWNSEND.
